(57) **CLAIM**

The ornamental design for a refrigerator-freezer, as shown and described.

DESCRIPTION

FIG. 1 is a right front perspective view of the design of the refrigerator freezer;

FIG. 2 is a front elevational view thereof. The ornamental design is not visible in a rear view, top plan view or bottom view;

FIG. 3 is a right side elevational view thereof, the left side elevational view being a mirror image; and,

FIG. 4 is an enlarged view of the pattern on the refrigerator-freezer doors of the embodiment of FIG. 1.

These portions of refrigerator-freezer in broken lines, specifically the surfaces of the refrigerator-freezer at the top and bottom edges of the doors and surfaces extending back from the doors including other surfaces of the refrigerator-freezer are not part of the claimed invention.
